UNITED STATES PATENT OFFICE.

PHILIP C. SIEGER, OF BROOKLYN, NEW YORK, ASSIGNOR TO THE BUTTERICK PUBLISHING COMPANY, OF NEW YORK, N. Y., A CORPORATION OF NEW YORK.

CUTTING GUIDE FOR DRESSMAKERS' PATTERNS.

Application filed July 23, 1920. Serial No. 398,406.

To all whom it may concern:

- Be it known that I, PHILIP C. SIEGER, a citizen of the United States of America, residing at Brooklyn, in the county of Kings and State of New York, have invented certain new and useful Improvements in Cutting Guides for Dressmakers' Patterns, of which the following is a full, clear, and exact description.
- 10 The paper patterns used by dressmakers in making garments are made in various shapes corresponding to the different parts of the garment and are also made in different sizes. In cutting out the garment 15 the pattern pieces are laid on the cloth and the latter is then cut around the edges of the pattern. It is desirable to lay the pattern pieces on the cloth in such manner as to leave the least waste, that is, to leave as few and as small unutilizable scraps of cloth as possible, but even experienced dressmakers find this a difficult art, and it is seldom if ever mastered by an amateur, such 20 as a housewife whose efforts at dressmaking are confined to making her own and her children's clothes. I have therefore been led to devise my present invention, which has for its object to provide a cutting chart or guide which the user can readily follow 25 without fear of error and which will enable her to utilize her material with the minimum amount of waste. To this and other ends the invention consists in the novel features hereinafter described.
- 30 In carrying out my invention I provide a chart in which strips of material of different widths are shown, as for example material ranging from thirty-five to forty-four inches in widths, and on these the pattern pieces 35 for the different sizes of the garment, say sizes 32, 34, 36, 38, 40, 42, 44, etc., are shown in outline, arranged in such relation to each other as will utilize the material to the best advantage, with the least amount of waste.
- 40 According to another feature of the invention the chart is provided with legends indicating what certain of the pieces are for, and suggesting uses for the scraps or pieces of material remaining after the garment parts 45 have been cut out.
- 45 In the accompanying drawing I have illustrated one of my improved layout-charts in plan. Therein *a*, *a'*, represent strips of material of the narrowest widths and shortest 50 lengths that can be conveniently used for

the particular garment and model, say material 35 or 36 inches wide, and on each strip the pattern pieces are shown in outline in the positions in which they should be arranged for cutting. Below the strips are 60 printed legends giving the width of the material and the sizes of the garment. Thus under strip *a* are the words "35 or 36 inch material sizes 32 to 38", by which the user is informed that with 35 or 36 inch material 65 the pattern pieces for a garment 32, 34, 36 or 38 in size are to be laid out as shown. The two selvedge edges are indicated by the word "Selvedge", so that in using material which comes folded lengthwise the user will not 70 make the mistake of arranging the pieces without unfolding the goods. In the space between pattern pieces 10 and 11 and between parts 4 and 6 on layout *a* are the words "Material for facing skirt", and at 75 the end of the strip the words "Material for lining sash". On layout *a'* these legends are between parts 11 and 13, at the right of 5, and at the end of the strip.

Similarly layouts *b* and *b'* illustrate, with 80 appropriate legends, the arrangements of the pattern pieces for using 44 inch material in making the garment in sizes 32 to 38 and 40 to 44.

It will be observed that with the exception 85 of parts 10 and 11 the parts are arranged differently in the different layouts, the object in each case being to utilize the material in the most effective and economical manner. It is to be understood that the 90 numerals applied to the pattern pieces in the layouts correspond to the identifying numerals with which the pattern pieces themselves are marked, as explained in the patent to Hannah G. Millard, No. 1,313,496 95 owned by The Butterick Publishing Company, to which my present invention is assigned.

In some cases the pattern outfit supplied to the customer includes pattern pieces for 100 making the same garment in several models or types, differing in various details, such as style of sleeves, neck, etc., though alike in respect to the major features of the garment. These different types are illustrated, usually 105 on the envelope containing the pattern, and are commonly marked "View A", "View B", etc. In such cases I provide on my cutting guide chart a series of layouts illustrating the proper arrangements for all the different 110

models. Thus in the drawing, layouts *a*, *a'*, *b* and *b'* are for the garment represented by "View A", and are so marked, while layouts *c*, *c'*, *d*, *d'*, are for "View B", and *e*, *e'*, *f*, *f'*, 5 are for "View C". It will be observed that model A does not have the piece 7 found in model B, and that model C lacks part 7, and also part 13. —

In a suitable position, say across the top, 10 the chart is provided with general directions, such as "Select the layout of view, width of material, and size of pattern to be used. Then lay pattern pieces on right side of material as placed in layout."

15 The use of my improved cutting chart not only saves material but also effects a marked economy of time. This is true even in the case of the professional dressmaker, who, with the help of skill, experience and natural aptitude, may be able to study out a cutting arrangement which will avoid undue waste of material. With my layout chart, 20 however, she arranges the pattern pieces at once, without any loss of time.

25 It is to be understood that the invention is not limited to the specific embodiment herein illustrated.

I claim:

1. A cutting guide for dressmakers' patterns, comprising a chart showing in plan a plurality of strips of material of different widths and showing in plan on the respective strips the pattern pieces laid out in different arrangements according to the widths 30 of material for the economical utilization 35

thereof, said strips having legends indicating uses, in the garment for more or less of the scraps remaining after the garment pieces are cut out.

2. A cutting guide for dressmakers' patterns, comprising a chart showing in plan a plurality of strips of material of different widths in sets corresponding to the different sizes of the garment to be made, each strip having in outline thereon the pattern pieces 40 arranged for the economical utilization of the material.

3. A cutting guide for dressmakers' patterns, comprising a chart showing in plan a plurality of sets of layouts, for different 50 models of the garment to be made; each set of layouts representing, for the respective model, the arrangement proper for the economical utilization of different widths of the material for different sizes of the garment. 55

4. A cutting guide for dressmakers' patterns, comprising a chart showing in plan a plurality of sets of layouts, for different models or styles of the garment to be made; each set of layouts representing, for the respective model or style, the arrangement proper for the economical utilization of different widths of the material for different sizes of the garment, and the several layouts 60 also having legends indicating uses, in the 65 garment, for scraps remaining after the garment pieces have been cut out.

In testimony whereof I hereto affix my signature.

PHILIP C. SIEGER.
